PORTABLE TOOL HAVING ROTARY DRUM FOR ACTING ON WORK SURFACE

Alma A. Hutchins, 49 N. Lotus Ave.,
Pasadena, Calif. 91107

Filed Mar. 9, 1970, Ser. No. 21,792

Term of patent 14 years

Int. Cl. D8—02

U.S. Cl. D8—62

FIG. 1 is a perspective view of a portable tool having rotary drum for acting on work surface embodying the invention;

FIG. 2 is a perspective view of the tool in inverted position, and with the handle turned through 180° to a changed position for better viewing in FIG. 2;

FIG. 3 is a side elevational view of the tool;

FIG. 4 is a top plan view of the tool, with the handle in the position of FIG. 1;

FIG. 5 is a bottom plan view of the tool, with the handle in the position of FIG. 2;

FIG. 6 is a rear elevational view of the tool with the handle in the FIG. 1 position; and,

FIG. 7 is a front elevational view with the handle in the FIG. 1 position.

I claim:

The ornamental design for a portable tool having rotary drum for acting on work surface, as shown and described.
